FLIER FOR SPINNING MACHINES

Harvey E. Herr, Buffalo, N. Y., assignor to Herr Manufacturing Company, Inc., Buffalo, N. Y., a corporation of New York

Application September 15, 1937, Serial No. 164,022

8 Claims. (Cl. 117—26.5)

This invention relates to certain new and useful improvements in the fliers employed in connection with spinning machines and the like.

It has for its chief object to provide a flier structure having simple and effective means for preventing the flier overrunning or continuing to revolve after the bobbin has come to rest, thereby to prevent kinking or looping of the twisted yarn.

Another object of the invention is to provide a braking device for fliers which is simple and inexpensive in construction, which is designed for ready assemblage to the flier structure, and which is of minimum weight.

Other features of the invention reside in the construction and arrangement of parts herein-after described and particularly pointed out in the appended claims.

In the accompanying drawing:—

Figure 1 is a fragmentary front view of a portion of a spinning machine showing the improved flier applied thereto. Figure 2 is an enlarged top plan of the flier and associated bobbin. Figure 3 is a bottom plan view of the flier. Figure 4 is an enlarged fragmentary vertical section taken in the plane of line 4—4, Figure 2. Figure 5 is an enlarged horizontal section of the hub and brake structure taken substantially in the plane of line 5—5, Figure 4. Figure 6 is a side elevation of the hub or sleeve of the flier body.

Similar characters of reference indicate corresponding parts throughout the several views.

The invention is applicable to spinning machines of any suitable and well known construction, 10 indicating the bobbin-spindle and 11 the take-off bobbin mounted thereon. The thread or yarn from the bobbin extends upwardly through the eyes of the flier wires 12, 13 mounted on a holder or flier-body applied to the bobbin-spindle and thence upwardly through a guide or centering eye 14 to a take-up spool (not shown). The bobbin shown is of the type used with fliers of the eccentric type and has a recess 15 in its top containing an inverted cup-like member 16 having an opening 17 therein arranged concentric to the axis of the bobbin-spindle.

The flier-body preferably consists of an attaching sleeve, hub or barrel 18 made of fiber or like material and adapted to be fitted over the bobbin-spindle. At its lower end this sleeve has an eccentrically-shaped flange 19 adapted to be passed through the cup-opening 17 during the application and removal of the flier to and from the spindle. Spaced above the eccentric flange is a circular flange 20 and fitted about a neck 21 rising from this flange and bearing or shouldered

against the top side of the latter is a base plate or spider 22 to which the flier wires 12, 13 are connected. The base plate has a depending tongue 23 adjacent its sleeve engaging opening which engages a companion notch 24 in the sleeve-flange 20 to lock the parts against relative rotation.

Extending about the sleeve-engaging opening of the base plate 22 is an outwardly-facing annular bead or flange 25 spaced from the top side 10 of said plate to provide an annular groove 26 in which is disposed a locking ring 27 for operative engagement with the inner ends of the flier wires for securely retaining them in the customary plate loops 28.

At its upper end the sleeve 18 terminates in an enlarged circular head or flange 29 and seated between the bottom face of this head and the base plate flange 25 is a split ring 30 which serves to effectually anchor the base plate to the sleeve. 20 It will be noted that the upper flange 29 is of less diameter than that of the lower flange 25 and slightly smaller than that of the base-plate opening, so that the base plate can be readily fitted to the sleeve 18.

The improved brake for preventing overrunning of the flier after the bobbin has come to rest is borne by the sleeve or hub 18 of the flier and preferably consists of a brake element 31 substantially in the form of a pin which is guided in an 30 opening 32 formed radially in such sleeve through the bore thereof, and which is adapted for frictional or braking contact with the bobbin-spindle 10. This brake element is, by preference, disposed between the sleeve-flanges 20 and 29 and 35 seated in an annular groove 33 between such flanges is a retaining spring 34 which extends over and bears against the head 35 of the brake element and constantly urges the latter into yieldable frictional contact with the bobbin spindle and resists outward displacement of such brake element from the sleeve. This retaining spring is made of spring wire and is substantially circular in shape, one end thereof terminating in an inwardly or radially-bent arm 36 which abuts edge-wise against the bottom of the groove 33 to resist its turning relatively to the sleeve.

By this construction, the braking element constitutes an inherent part of the hub structure of the flier, and it does not disturb the balance factor of the flier nor add materially to its weight. Furthermore, the braking elements may be readily assembled and in the structural assembly of the other parts of the flier the brake element 31 and its spring 34 are permitted the necessary freedom 50 55

of movement required without interference with other parts of the flier-assembly.

I claim as my invention:—

- 5 1. A flier for spinning machines and the like, comprising a sleeve adapted for attachment to a bobbin-spindle, a wire-base mounted thereon, and braking means applied to said sleeve for engagement with the bobbin-spindle.
- 10 2. A flier for spinning machines and the like, comprising a body adapted for attachment to a bobbin-spindle, and a brake element guided radially of said body for frictional engagement with the bobbin-spindle.
- 15 3. A flier for spinning machines and the like, comprising a body having a bore adapted for attachment to a bobbin-spindle and having an opening therein extending through its bore, and a braking element fitted in said body-opening and including spring means for urging it into frictional contact with the bobbin-spindle.
- 20 4. A flier for spinning machines and the like, comprising a body having a bore adapted for attachment to a bobbin-spindle and having an opening therein extending through its bore, a braking element fitted in said body-opening for contact at its inner end with the bobbin-spindle, and a spring applied to said body and bearing against the outer end of the braking element for urging it toward the spindle.
- 25 5. A flier for spinning machines and the like, comprising a body having a bore adapted for attachment to a bobbin-spindle and having an opening therein extending through its bore and an exterior annular groove intersecting said opening, a braking element fitted in said body-opening for contact at its inner end with the bobbin-spindle, and a spring fitted in said annular groove and bearing against the outer end of the braking element for urging it toward the spindle.

6. A flier for spinning machines and the like, comprising a hub-sleeve adapted for attachment to a bobbin-spindle and having spaced upper and lower flanges thereon, a wire-base fitted on said hub between said flanges, a brake element applied to said hub-sleeve for engagement with the bobbin-spindle, and a spring applied to the hub-sleeve in the space between its flanges for urging said brake element in frictional engagement with said spindle.

7. A flier for spinning machines and the like, comprising a hub-sleeve adapted for attachment to a bobbin-spindle and having spaced upper and lower flanges thereon and an annular groove in the space between said flanges, said sleeve having a substantially radial opening therein intersecting said groove, a brake element slidably fitted in said opening for engagement at its inner end with the bobbin-spindle, and a substantially circular spring fitted in said sleeve-groove and bearing against the outer end of said brake element for urging it into frictional contact with the spindle.

8. A flier for spinning machines and the like, comprising a body having a bore adapted for attachment to a bobbin-spindle and having an opening therein extending through its bore, a braking element fitted in said body-opening for contact at its inner end with the bobbin-spindle, and a substantially circular spring fitted about said body and bearing against the outer end of the braking element for urging it toward the spindle, said spring terminating at one end in an inwardly-bent arm abutting the contiguous portion of said body.

HARVEY E. HERR.
